UNITED STATES PATENT OFFICE.

OWEN PETERSON HERWICK, OF PORTLAND, OREGON.

COASTER.

1,362,865.

Specification of Letters Patent. Patented Dec. 21, 1920.

Application filed March 16, 1920. Serial No. 366,234.

To all whom it may concern:

Be it known that I, OWEN PETERSON HERWICK, a citizen of the United States, residing at No. 1025 South Jersey street, St. 5 Johns, city of Portland, county of Multnomah, and State of Oregon, have invented a new and useful Coaster, of which the following is a specification.

This invention relates in general to 10 coasters, or so-called skipmobiles, and has reference more particularly to propelling or traction means for this general class of vehicles.

As heretofore employed these coasters and 15 the like, which have recently become prominent as a child's toy, have usually relied on the manipulator to furnish the traction necessary by placing one foot on the coaster and using the other foot to impart the necessary push to the same. While this manner 20 of manipulation has proven sufficient as a propelling force, the constant sliding of contact of the manipulator's foot on the ground surface over which the coaster traverses very 25 soon wears out his shoe and for this reason makes the use of coaster undesirable. Then, again, aside from these disadvantages, the pleasure experienced in using a coaster without some mode of self traction takes away 30 some of the pleasure which is present in a mechanically propelled coaster.

According to the present invention, it is proposed to equip or provide a coaster or 35 the like, such as a skipmobile with a mechanical propelling or traction inducing device which will overcome the above mentioned disadvantages and at the same time provide a novel manner of operation or manipulation.

40 In the accompany drawing which illustrates one form of the invention:

Figure 1 is a side elevation illustrating the application of the idea;

Fig. 2 is a plan view;

45 Fig. 3 is a sectional view taken on the line 3—3, Fig. 1.

Fig. 4 is a perspective view of the skid or shoe which is used as a propelling means and

50 Fig. 5 is a plan view of the rear wheels and rollers showing the manner of supporting the coaster frame thereon.

Referring now to the drawing in detail, the coaster or skipmobile may be constructed in any desirable manner and for the sake 55 of economy as well as other commercial rea-

sons should comprise a horizontal frame 1 relatively narrow in transverse section and sufficiently long to meet requirements.

This frame will be equipped with rear wheels or rollers such as 2 having an axle 3 60 with a yoke or the like 4 mounted thereon and adapted to fixedly support the rear end of the frame 1.

The front of the frame 1 should be provided with a convenient means, such as the 65 sleeve 5, adapted to receive the spindle or shaft of the yoke 6 which is provided with oppositely spaced bearings 7 providing a mounting for the axle 8 of the front or steering wheel 9. The spindle or shaft of the 70 yoke 6 terminating in the bifurcated end 10 is made to receive and confine by a pivotal connection the end of the steering column 11 which is constructed with handle bars such as 12. 75

The construction of the coaster so far is more or less conventional and as now used the operator or manipulator usually rests one foot at a convenient location on the frame 1 and uses the other foot as a propelling medium. 80

According to the form of invention illustrated, the operator will as heretofore mentioned place one foot on the frame 1 preferably a forward location where his toe will 85 abut against the upwardly extending toe bearing 13 and insert his other foot through the strap 14 which together with the instep block 15 and the oppositely disposed horizontal ends 16 of the frog 17, will provide 90 a stirrup. The frog 17 is preferably constructed of two pieces of sheet metal with its lowermost ends bent outwardly as are the ends 16 to provide maintaining flanges 18 95 for the shoe or skid 19. The frame 1 is provided with a relatively long slot 20 which extends along a medial line of the coaster from a point adjacent the rear axle 3 to a point slightly forward of the middle of the frame. This slot is made to receive the 100 web portion 21 of the frog 17 so that the shoe or skid 19 is mounted free to slide longitudinally of the coaster. In order to normally maintain the skid or shoe 19 out of engagement with the surface over which the coaster traverses a spring 22 is provided on each side of the web 21 and so arranged that its respective ends will contact with the frame 1 on opposite sides of the slot 2 and with its middle fixed to the underside of the 110

ends 16. The curvature of each of these springs is such as to lift the skid 19 off the ground, but the influence of the same may be overcome when the manipulator with his one foot in the stirrup supports his weight on this foot and imparts a downward thrust on the skid or shoe. The moment his weight is released the tendency of the springs 22 is to lift the shoe 19.

10 In operation when the weight of the manipulator is imposed on the support for the shoe or skid 19 the same will contact the ground surface and by imparting a rearward push to the shoe, when thus contacting 15 with the ground surface, the coaster will be propelled forward and the moment the skid reaches its limit of rearward movement, the manipulator will then release the compression on the springs permitting them 20 to lift the skid and enable the same to be brought forward to the limit of its forward movement in the slot where the operation may be repeated.

25 In this way, the coaster may be propelled without requiring the manipulator to slide his foot over the surface of the ground.

30 As a further feature to be realized by the invention attention is called to the possibility of using the shoe or skid as a brake in which event the weight of the manipulator could very easily be imposed on the stirrups and without necessarily imparting a rearward thrust to the shoe, the shoe could be caused to contact with the surface over

which the coaster was traversing and act as 35 a brake skid.

I claim:

1. A coaster, including a wheeled frame, a longitudinal slot in said frame, a shoe hung below said slot having a web portion which 40 extends through said slot, a foot engaging means mounted to said web portion above said slot, and spring means associated with said foot engaging means for normally maintaining the said shoe out of contact 45 with the ground surface but adapted to be overcome by the foot of the operator for moving the shoe rearward of the coaster in contact with the ground surface.

2. A coaster including a wheeled frame 50 with steering means, a longitudinal slot in said frame and propelling means adapted to slide back and forth in said slot, comprising, a shoe hung below the frame and parallel therewith, a web portion connected to the 55 shoe and extending through said slot with a foot engaging means on the end thereof, and leaf springs arranged between the foot engaging means and bearing upon the frame 60 on opposite sides of the slot, said spring adapted to normally maintain the shoe out of contact with the ground surface, but capable of permitting the foot of the operator to move the shoe in contact with the ground surface and rearward of the coaster for imparting a push to the coaster.

OWEN PETERSON HERWICK.
